UNITED STATES PATENT OFFICE

109,710

DESIGN FOR A SCALE

Max Garbell, Chicago, Ill.

Application March 5, 1938, Serial No. 75,620

Term of patent 14 years

To all whom it may concern:

Be it known that I, Max Garbell, a citizen of the United States of America, and a resident of Chicago, Cook County, Illinois, have invented a new, original, and ornamental Design for a Scale, of which the following is a specification, reference being had to the accompanying drawing forming a part thereof.

The figure of the drawing is a perspective as viewed from the front of the scale, showing my new design.

I claim:

The ornamental design for a scale substantially as shown.

MAX GARBELL.
